CLAIM

The ornamental design for a holder for bath accessory, as shown and described.

DESCRIPTION

FIG. 1 is a front elevational view of a holder for bath accessory showing my new design, the rear elevational view being identical in appearance;

FIG. 2 is a left side elevational view thereof;

FIG. 3 is a right side elevational view thereof;

FIG. 4 is a top plan view thereof;

FIG. 5 is a bottom plan view thereof;

FIG. 6 is a perspective view thereof;

FIG. 7 is a perspective view thereof with a soap dish mounted therein, and the broken line showing of a soap dish is for illustrative purposes only and forms no part of the claimed design; and,

FIG. 8 is a perspective view thereof with a cup mounted therein, and the broken line showing of a cup is for illustrative purposes only and forms no part of the claimed design.
